UNITED STATES PATENT OFFICE.

OLIVER DWIGHT WOODRUFF, OF SOUTHBURG, CONNECTICUT.

LANTERN.

SPECIFICATION forming part of Letters Patent No. 408,783, dated August 13, 1889.

Application filed March 1, 1889. Serial No. 301,690. (No model.)

To all whom it may concern:

Be it known that I, OLIVER DWIGHT WOODRUFF, residing at Southington, in the county of Hartford and State of Connecticut, have invented certain new and useful Improvements 5 in Lanterns; and I do declare the following to be a full, clear, and exact description of the same, reference being had to the accompanying drawings, which form a part of this specification.

My invention relates to an improvement in tubular lanterns, the object being to simplify, improve, and cheapen their construction and to increase their convenience in use over lanterns of this class as heretofore made.

With these ends in view my invention consists in a tubular lantern having certain details of construction and combinations of parts, as will be hereinafter described, and 15 pointed out in the claims.

In the accompanying drawings, Figure 1 is a view in front elevation of a lantern embodying my invention. Fig. 2 is a view thereof in rear elevation, with the upper portion of 25 the lantern shown in vertical central section. Fig. 3 is a detached plan view of the perforated burner-plate. Fig. 4 is an enlarged view, in transverse section, of the guide-tubes which inclose the lifting-spring. Fig. 5 is a detached 30 reverse plan view of the globe-cap draft-chest; and Fig. 6 is a detached view of such parts in vertical section; and Fig. 7 is a detached view of the burner-plate, the guiding-tubes, the loop, and the notched ear.

The lantern herein shown is provided with 35 a base A, which contains the fount, draft-tubes B B, a burner C, and a perforated burner-plate D, having a central opening adapting it to fit over the burner and forming the lower 40 support for the globe E of the lantern. This plate is automatically lifted for raising the globe above the burner by means of a spiral spring F, inclosed within a tube G, depending from its edge and telescoping in a larger 45 tube H, standing up from the base of the lantern and by preference soldered for strength to the curved lower end of the adjacent draft-tube. These two tubes G and H are adapted 50 in themselves to guide the plate, and hence the globe, as the same are lifted and pulled down by being coupled together, so as to be

relatively non-rotatable. As herein shown, they are adapted to guide the plate and globe by providing them with corresponding longitudinal corrugations or flutings I, those of one 55 tube being adapted to fit within those of the other, so as to permit the tube attached to the burner-plate to telescope freely in the tube attached to the base of the lantern, but preventing the former from rotating within 60 the latter, whereby the vertical movement of the plate and globe is strictly confined to one vertical plane and the use of any other guides for the globe rendered unnecessary.

Instead of fluting or corrugating the tubes, 65 as described, they may be adapted in any other suitable manner to perform the guiding function set forth above, and so dispense with special guiding attachments or the use of another set of telescoping tubes, as has been here- 7c tofore proposed.

The burner-plate is held in its normally-depressed position against the tension of the spiral lifting-spring by means of a catch J, consisting of a rigid notched ear depending 75 from the edge of the plate at a point near the tube G and having its slotted edge facing such tube, and by a long loop K of wire having its loop end uppermost and secured to the base of the lantern at a point near the 80 tube H, so as to stand in a virtually upright position. Under this construction and arrangement of parts the loop is readily disengaged from the catch by pressing it toward the tube H, which serves as a support for the 85 fingers during this operation. The lower end of the catch is beveled, so that the catch will automatically re-engage with the loop when the plate is pulled down by means of the finger-piece L, which is rigidly secured to the 90 burner-plate and extends horizontally beyond the edge thereof.

The globe-cap M of the lantern is rigidly secured to the rectangular lower end of a long and narrow draft-chest N, having straight 95 sides and straight ends and a curved top, which conforms to the outline of the curved upper ends of the draft-tubes B B, with which the said chest extends parallel. A long rectangular opening leads from the globe-cap 100 into this draft-chest, which greatly promotes the draft of the lantern, which will therefore

sustain a larger and a brighter flame than a lantern having the ordinary central draft-tube.

The globe E is retained in place upon the 5 burner-plate by means of globe-retaining devices O and P, while the upper end of the globe is supported and guided in a laterally-yielding globe-holder Q, the said devices O and P and holder Q having been fully 10 scribed and claimed by me in an application filed on the 26th day of January, 1889, and therefore not requiring extended description here.

By adapting the guide-tubes to constitute 15 in themselves the guides for the globe the lantern is much simplified and cheapened, and not only that, but also the globe is freed from cumbrous guiding devices, which are unsightly and liable to be injured and deranged 20 in the use of the lantern. The catch and spring for holding the globe down are placed where they will not be heated and where they are very conveniently operated. The increased draft secured by the draft-chest enables 25 the lantern to sustain a larger and brighter flame, as has been described.

I am aware that a circular draft-chamber into which the upper ends of the draft-tubes of a tubular lantern enter is not new. In 30 chambers of that form the air is diffused and not moved directly, as in my draft-chest, which secures better results.

I would have it understood that I do not limit myself to the exact construction and arrangement of parts herein shown and described, but hold myself at liberty to make such changes and alterations as fairly fall within the spirit and scope of my invention.

Having fully described my invention, what I 40 claim as new, and desire to secure by Letters Patent, is—

1. In a tubular lantern, the combination, with the base thereof, of a vertically-movable burner-plate, two telescoping tubes respectively secured to the burner-plate and to the 45

lantern-base and coupled to be relatively non-rotatable, and means for lifting the plate, which is prevented from moving laterally by the coupled tubes, substantially as set forth.

2. A tubular lantern having a movable 50 burner-plate, two telescoping tubes respectively secured to the plate and to the base of the lantern and constructed to confine the plate to vertical movement in one plane, a spring for automatically lifting the plate, a 55 catch consisting of a notched ear rigidly secured to and depending from one edge of the plate, and a long loop for engagement with such catch, secured to the base of the lantern and standing in a virtually upright position, 60 substantially as set forth.

3. In a tubular lantern, the combination, with the draft-tubes thereof, of a fixed globe-cap located below the curved upper ends of the said tube and a long narrow draft-chest 65 extending parallel with the said curved ends of the tubes and opening into them at its upper end and at its lower end into the globe-cap, substantially as set forth.

4. In a tubular lantern, the combination, 70 with the draft-tubes thereof, of a fixed globe-cap located below the curved upper ends of the said tubes, a fixed globe-holder depending below the cap and adapted to have the upper end of the globe play up and down in 75 it, a globe, an automatically-lifted burner-plate, and a long narrow draft-chest extending parallel with the said curved ends of the tubes and opening thereinto and interposed between them and the globe-cap, with the interior of which it communicates through a long narrow opening, substantially as set forth.

In testimony whereof I have signed this specification in the presence of two subscribing witnesses.

OLIVER DWIGHT WOODRUFF.
